FIG. 7

UNITED STATES PATENT OFFICE.

HOWARD C. FORBES, OF CAMBRIDGE, MASSACHUSETTS.

CLIP.

Application filed July 26, 1917. Serial No. 182,866.

To all whom it may concern:

Be it known that I, HOWARD C. FORBES, a citizen of the United States, residing at Cambridge, in the county of Middlesex and State of Massachusetts, have invented new and useful Improvements in Clips, of which the following is a specification.

This invention relates to improvements for clips for fastening papers and the like. 10 More particularly it relates to spring wire devices for binding together sheets, pamphlets or other loose leaves. Although there is a great commercial demand, and enormous daily consumption, of devices of this class, 15 and although numerous varieties of them have been proposed, all hitherto known, so far as I am aware, fail to give satisfactory service except in limited ways. Among the defects of various existing devices, which the 20 present invention seeks to remedy, are failure to hold sheets securely; extension too far over the page; projection outward from the edge of the binding; and possession of only such gripping power as results from 25 lateral displacement of spring jaws to a distance equal to the thickness of the matter to be bound.

Among the advantages combined in the invention are that, when in use, the device 30 does not project out from the edge of the bound packet; does not project over the bound leaves beyond the ordinary width of margin; terminates there in a straight line 35 parallel with the edge of the packet, instead of in a projecting point or points, applies its gripping power along this line, at a safe distance from the margin, so that the leaves turn about it as about a hinge, and so that the opening of the leaf does not exert a 40 leverage to open or release the fastening; holds with a grip between parallel jaws, as contrasted with the grip between mere crossed wires at present commonly used; operates with multiple intensity of pressure 45 as compared with the ordinary grip resulting from such mere displacement of two clamping wires as is occasioned by the insertion between them of the package that is to be bound; is capable of relatively wide 50 opening and binding; is opened widely without serious effort of the user and without destruction of its own elasticity: does not lose its efficiency of grip owing to thickness of package, within wide limits, and 55 has in its jaws a degree of independent gripping power additional to that derived from

the torsion of the main spring at the edge of the package. Withal, it is also among the ideals attained by the invention that it makes a spring clip at low expense for material and labor and with few operations in the manufacture. It is the object of the invention to provide a device having the foregoing and the other advantages that characterize the fastener hereinafter described. In 60 the accompanying drawings which illustrate one embodiment of the invention,

Figures 1, 2 and 3 show an embodiment of the invention in which Figure 2 may be considered as a plan, with the device lying 70 on a table, Figure 1 a view when the device has been rotated 90° so that its edge which is upmost in Figure 2, has come in view, and Figure 3 a view when the device has been rotated 90° from Figure 2 so that the edge 75 which is lowest in Figure 2 has come into view.

Figures 4, 5, 6 and 7 illustrate successive positions of the device in applying it to a 80 package of papers, when in use;

Figure 8 is an edge view of Figure 7; and Figures 9 and 10 illustrate modifications.

As shown in the drawings the device consists of a single piece of wire, which should be spring wire and which is formed in the 85 general shape of a trapezoid having oblique sides equal. The wire has five portions, marked respectively 10, 11, 12, 13 and 14, separated by the four angles of the trapezoid. However, the device is not necessarily 90 of this specific shape. The portions 10 and 14 are parallel and constitute what are here called the jaws of the fastener. The portion 12 which is approximately parallel to them and which as seen in Figure 2 and Figures 95 4-7 appears to be perfectly parallel, is the shorter of the parallel sides of the trapezoid and constitutes a torsion spring, one end of which is connected with jaw 10 by arm 11 which is one of the oblique sides, and the 100 other end of which is connected with the other jaw by the other oblique side of the trapezoid. In the preferred form of the invention the jaws 10 and 14 stand at a little 105 distance apart from each other when at rest, as clearly seen in Figure 1. Unlike the previously known and ordinary fasteners, in which the papers that are to be bound come under compression as they are inserted between the jaws by the pressure resulting 110 from the spreading of the jaws, the jaws here are not much displaced by introduction

of the package. The binding pressure is obtained otherwise, and occurs between the two sides of these jaws which in Figure 1 are remote from each other. In Figure 2, assuming that the parts 13 and 14 are lying flat on the table, the parts 10 and 11 will stand a little above them and hence the jaw 10 appears to be a little nearer the spring back 12 than the jaw 14. It may be actually so or may be as far from it as is the jaw 14; but if it be slightly nearer the operation by which this jaw 10 passes to the other side of the jaw 14 will be facilitated, particularly when the fastener is made with heavy wire.

The back 12 is preferably set askew. In the embodiment represented in Figure 3, the plane defined by the jaw 14 and arm 13 makes such an angle with the plane defined by jaw 10 and arm 11 that the back 12 joining those two arms 13 and 11 lies at a slight angle with the parallel jaws 10 and 14, as seen when these parts are looked at edgewise of the device, although when viewed sidewise they may appear parallel as seen in Figure 2. The degree of this skewing may vary depending, for example, upon the size of the device, or the size of its wire, or the thickness of package for which it is designed. While notable advantages follow from this feature, the usefulness of the device is not destroyed by diminishing it, or even by omitting it. In Figure 9 a modification is shown in which there is less of a skew, so little in fact that the spring back 12' is strictly parallel with the jaws 10' and 14'. In Figure 10 is shown a form in which the jaw 14'' and its arm 13'' are in a plane parallel to the plane in which the jaw 10'' and arm 11'' are. In this case the spring back 12'' joining them runs obliquely between the arms 11'' and 13'' the obliquity being in the opposite direction from that shown in Figure 3. For some uses this may suffice, but for best results in binding sheets which are rather stiff the form of Figure 3 is to be preferred because when in use as illustrated in Figure 8 the spring back 12 lies obliquely across the edge of the package with its obliquity in the appropriate direction for allowing each jaw and its associated arm to lie parallel with the sides of the package to which the fastener is applied.

The spring back 12 whether strictly parallel or only approximately parallel to the jaws, or even if departing considerably from parallelism, as it may in special cases if one of the arms is longer than the other, constitutes a torsion spring capable of being twisted by the arms 11 and 13. Owing to its length it has capacity for undergoing a considerable degree of twisting without acquiring a permanent set or without its elastic limit being passed. According to the torsional characteristics needed the

length of this back may be varied, in designing the fastener for adaptability to particular duty.

The jaw 10 is short enough for its end to swing from one side of the jaw 14 to the other, passing between that jaw and the back.

The jaw 14 preferably has a projecting end extending beyond the corner between jaw 10 and arm 11. This facilitates the application of the device to the package which is to be bound. In use the device may conveniently be held in the left hand while the edge of the package of papers, that is to be bound, is resting against the extended end of the jaw 14, and is introduced between the jaws, the curvature between jaw 10 and arm 11 acting as a contracting throat which receives and guides the papers into the space between 10 and 14 to the position illustrated in Figure 4. The fastener may thus be pushed to the position illustrated in Figure 5 with great ease. The side *a* of jaw 10 is toward jaw 14. The fastener has been disturbed from its normal position of rest only slightly. Then by simply swinging part 12 about the jaws 10, 14 as an axis for about 180°, from the position of Figure 5 where it lies below the jaws on the face of the package to that of Figure 6 where it lies above them, the fastener is put under tension. The jaws 10 and 14 thus shift their position, relative to each other, the side *a* of jaw 10, which was toward jaw 14, passes to the other side of that jaw and to a position where it is on the side of jaw 10 that is remote from jaw 14. The side *b* of jaw 10, which originally was remote from jaw 14 becomes the clamping side of jaw 10. While in this position the fastener does not lie flat on a package having parallel sides, and is not in stable equilibrium; but by rotating the fastener in the plane of the package, from the position of Figure 6 to that of Figure 7, it comes into what may be called stable equilibrium, and is locked in that position. An edge view of this is seen in Figure 8. The degree of distortion from the normal position of the parts when at rest may be understood by comparing Figure 3 with Figure 8, assuming Figure 3 to be rotated so as to stand parallel with Figure 8. The jaw 10, which in Figure 8 is on the right of jaw 14, originally stood on the other side 120 of it; and the skew back 12, which originally, as in Figure 3, was the middle portion of a reverse curve, constitutes in Figure 8 a direct connection between the arm 13 and jaw 14 on the back side of 125 the package and the arm 11 and jaw 10 on its face. Assuming, for example, that a specimen of the device is so made that when it is at rest the jaws 10 and 14 stand with a clear space of $\frac{1}{16}$ of an inch between 130

them, and are made of wire $\frac{1}{16}$ of an inch in diameter, the insertion between them of a package of sheets $\frac{3}{16}$ of an inch thick would spread them apart only $\frac{1}{8}$ of an inch.

5 This would be the positions of Figures 4 and 5, and the torsion set up in the spring piece 12 would be comparable to that obtained by mere spreading of wires as has been customary heretofore. But in the 10 positions of Figures 6, 7 and 8, the clamping side *b* of jaw 10 is distant from its original position as much as the total of the thickness of package, plus the thickness of the jaw 14, plus the space which 15 originally intervened between that jaw and jaw 10, plus the thickness of jaw 10. In the example taken for illustration this totals $\frac{3}{8}$ of an inch. The torsion of spring 12 is consequently made greater by this multi- 20 ple displacement than by merely pushing the papers between the two jaws, and in the direction opposite to that in which it was when the papers were merely pushed between the two jaws. The manoeuvre of 25 thus transferring the jaw 10 from one side to the other of jaw 14 is easily executed. The springiness of each of the jaws and of their connecting arms 11 and 13 allow them to yield, for one to pass the other.

30 When the corner portion between jaw 10 and arm 11 is transferred to the other side of jaw 14, by the manipulated rotation about the jaws as above mentioned, it is accomplished by displacing the whole arm 35 11 from one side of the plane of arms 13, 14 to the other side of their plane; and this means that the action is accompanied by torsion of the arm 13, for the portion 12 at one end of portion 13 twists the portion 40 13 whose other end is held at its corner with the jaw 14 on the back side of the package. The jaw 10 having been originally in a certain plane with arm 11 tends to remain in a plane extending in the same 45 angular direction therefrom; and its tip, therefore, tends to remain on the side of jaw 14 on which said tip originally was, even after the arm 11 has been transferred, because the movement of the arm 11 has been a sort of rotation about the end of 50 arm 13 where it is joined to the back 12. However, the physical substance of the package thrusts the tip of this jaw 10 as far to the second side of jaw 14 as its corner next to arm 11 is thrust, assuming that 55 the package has parallel sides. This is a further distortion, improving the grip on the package, so that the jaw 10 presses throughout the whole of its length. How- 60 ever far the corner between 12 and 11, which is one end of the jaw shall be displaced, the other end of the jaw tends not to be displaced so much, and therefore resists its displacement with a constant pressure along 65 its whole length, and this appears to be

occasioned mainly by the torsion of the portion 11. The skewed arrangement of the back causes the parts 11 and 10 to lie flat on one side of the package, and the arm and jaw 13 and 14 to lie flat on the other 70 side of the package. Experience shows that the loose leaves of the package thus bound together are held with a firm grip, and that this grip is applied along the entire length of the jaws 10 and 14. As 75 these jaws are parallel to the margin of the package, and as they are at the extreme distance to which the device reaches from the margin, the leaves of the package may be turned up around the jaw 10 as around 80 a hinge, without exerting any leverage tending to loosen the grip of the jaws upon the package.

The several different turning movements described and illustrated can in practice be 85 accomplished with a very quick composite motion which is easily learned. The turning that occurs between Figures 5 and 6, and that which occurs between Figures 6 and 7 can be executed during the sliding-on 90 movement which occurs between Figures 4 and 5. As the binding effect is applied at the jaws, rather than at the edge of the package, the device can be used for binding together sheets of incompressible material, 95 or of stiff material. The insertion of a package of any thickness is relatively easy because of the initial set of the jaws, with a space between them. This space may be designed of as small a minimum as is de- 100 sired, depending upon the duty to be served, and many other variations may be made from the specific form of the device illus- 105 trated, as for example, by varying the relative length of the spring back, to weaken or strengthen the torsion effect, or varying its angle, to adapt the fastener to hold securely packages of considerable thickness, across the back of which package the spring 110 back is to run obliquely from the plane of one side or even beyond that plane, to the plane of the other side, or even beyond it, without detracting from the application of the binding pressure at whatever dis- 115 tance the jaws are from the back.

In designing fasteners according to the invention, it is not necessary to adhere to the four-sided structure illustrated, although that has many advantages. A fastener with a larger number of sides will 120 ordinarily be divided into the four parts herein described, in a virtual or functional sense, however great the number.

I claim as my invention:

1. A package comprising the combination 125 of a stack of separate elements with a continuous wire clip binding them frictionally together, said clip having two parallel jaws extending parallel to the adjacent edge of the package around which the portion 130

of wire connecting them passes the construction and arrangement being such that they are held by the intervening package on opposite sides of each other from those which they tend to occupy, whereby the frictional binding is produced; and the clip being turned so as to prevent upsetting from its position of unstable equilibrium, and so prevented from rotating around said jaws pursuant to said tendency by the arrangement of the clip with the sides adjacent to said jaws on opposite sides of the package.

2. The method of binding a package of sheets with a wire frictional clip, having two parallel jaws connected by arms to opposite ends of a torsional back, comprising the application of the clip to the package with the jaws extending inward, per-

pendicular to the edge thereof and on opposite sides thereof; rotating the clip about 180° , around the axis of the jaws, from a position of parallelism with the package on one side thereof to a portion of parallelism therewith on the same side, thereby spreading the jaws and placing the back under torsion; and then rotating the clip about 90° around an axis perpendicular to the plane thereof, thereby injecting the marginal portion of the package between said arms whereby it prevents their reverse rotation about the first mentioned axis and maintains the pressure between the jaws in a line parallel to the margin.

Signed by me at Boston, Mass., this fifth day of June 1917.

HOWARD C. FORBES.
